UNITED STATES PATENT OFFICE.

PRESLEY D. VAN DEVENTER, OF SALISBURY, MISSOURI.

EXPRESS-CAR.

SPECIFICATION forming part of Letters Patent No. 375,232, dated December 20, 1887.

Application filed February 21, 1887. Serial No. 228,396. (No model.)

To all whom it may concern:

Be it known that I, PRESLEY D. VAN DEVENTER, of Salisbury, in the county of Chariton and State of Missouri, have invented a certain new and useful Improvement in Railway-Cars for Express Companies, of which the following is a full, clear, and exact description, reference being had to the accompanying drawings, forming part of this specification.

This car has an outer compartment, with a messenger for the delivery of express packages at each station, and an inner bullet-proof compartment which cannot be entered from the outside of the car and in which the valuable packages are stored, the packages for each station being passed from such strong-room or compartment into the other compartment in time for delivery at the next station. There are projections at the sides, ends, top, and bottom of the strong-room, which contain lamps by which the car is illuminated on the outside and peep and port holes through which the messenger in the strong-room can look and fire at robbers upon the outside. There is an alarm-bell, which may be sounded by the messenger, but which cannot be reached by anyone on the outside. The strong-room has also shot-proof ventilators.

Figure I is a side view of a car having my improved construction. Fig. II is an enlarged horizontal section at II II, Fig. I. Fig. III is an enlarged detail vertical section at III III, Fig. I. Fig. IV is an enlarged detail vertical section at IV IV, Fig. I. Fig. V is an enlarged detail vertical section at V V, Fig. I. Fig. VI is an enlarged detail vertical section at VI VI, Fig. II.

The sides of the car are shown at 1, the ends at 2, the top at 3, and the floor at 4. 5 is the outer compartment, which may be entered by a door, 6, in the side of the car or in other place. No novelty is claimed in the outer compartment *per se*. It may be supplied with means of defense similar to those described in connection with the inner compartment or strong-room, 7. The strong-room may have metal sides, ends, floor, and roof to render it bullet-proof, or it may have metal lining, as shown at 8, Fig. II. The sides and outer end of the strong-room have metal extensions 9, which project beyond the walls of the car, and which

have apertures 10 and 11. The apertures 10 are port-holes, through which the messenger may fire, and which are so constructed that any person may be shot, even if standing close to the wall of the car. The apertures are closed at the will of the messenger by sliding plates 12 or by any other suitable means. The apertures 11 are to allow the passage of light from a lamp, 13. The lamp is so arranged that it cannot be injured from the outside, the flame alone being in line with the aperture. The lamp-chamber 14 is backed by a metal plate, 15, so that a bullet passing through the aperture 11 could not reach the messenger. The floor has a metal turret, 16, extending downward, forming a chamber, which contains a lamp, 17, and which has apertures 18, through which the light of the lamp may shine along the bottom of the car, and port-holes 19, through which the messenger may see and may fire beneath the car in all directions. The apertures or port-holes 19 may be closed by shutters 20.

21 is a removable grating used to cover the sunk turret and yet allow the passage of air. 22 is a metal turret made on the roof of the car, containing apertures 23 and 24. The apertures 23 are for the messenger to see along the roof of the car, and through which he may fire along the roof. The apertures 24 are to allow light from the lamp 25 to pass and to allow sound to pass from the gong 26. The gong may be used to sound an alarm, and may be of such a size and character that it will be heard miles away. 27 is a hammer with which the gong 28 may be struck, and 29 is the pull-cord of the hammer.

29 are port-holes in the partition 30 between the two compartments 5 and 7. These port-holes may be closed by shutters 31 under control of the messenger within the strong-room, so that, while he may use them to see into the outer compartment, no one can use them to annoy or endanger this messenger.

32 is the aperture through which the express matter enters or leaves the strong-room. This is closed by a strong shutter or door, 33, which is solely under control of the messenger in the strong-room.

The apertures through which the light of the lamps passes may be closed by glass or may be left open. Any of the port-holes or the

other holes in the roof-turret may be used for ventilation; but I also provide special shot-proof ventilators 34, in which the air-passage is traversed by flat metal bars 35 set at different angles, so that a ball could not pass through the zigzag way between the bars.

It is understood that the messenger in the strong-room would be supplied with a dark-lantern, and that none of the lamps intended to cast light without the car would give any light within the strong-room.

I claim as my invention—

1. A bullet-proof compartment in a car, having outwardly-projecting parts on the walls, having port-holes and shutters adapted to close

said openings and controlled by a person within the compartment, substantially as and for the purpose set forth.

2. A bullet-proof compartment in a car, having projecting parts containing lamps shining through apertures in these parts and having port-holes, substantially as and for the purpose set forth.

3. A car-ventilator having cross-bars of flat metal set angularly with each other, substantially as and for the purpose set forth.

PRESLEY D. VAN DEVENTER.
